JAMES KEISTER, OF STEUBENVILLE, OHIO.

INTERNAL-COMBUSTION ENGINE.

1,134,867.

Specification of Letters Patent.

Patented Apr. 6, 1915.

Application filed November 25, 1913. Serial No. 802,917.

To all whom it may concern:

Be it known that I, JAMES KEISTER, a citizen of the United States, and a resident of Steubenville, in the county of Jefferson and State of Ohio, have invented a new and Improved Internal-Combustion Engine, of which the following is a full, clear, and exact description.

This invention relates to internal combustion engines of the four-cycle type, and particularly to engines of that character wherein in the admission of the explosive fluid and the exhaust of the spent gases are controlled by a single tubular valve which surrounds

15 the piston of the engine.

More specifically, the invention relates to an engine of that type disclosed in my pending application for Letters Patent, Serial Number 770,347, filed May 28, 1913, wherein 20 the tubular valve is provided with separate inlet and exhaust ports and has a two-step stroke in one direction for opening the exhaust port during one step and closing the exhaust port and opening the admission port 25 during the next step, said steps being synchronous respectively with the exhaust and suction strokes of the piston, and in the return movement the piston moves in one step to close the ports during the compression 30 and firing strokes.

The general objects of the invention are to improve and simplify the construction of the valve-operating mechanism so as to be reliable and efficient in use, comparatively 35 inexpensive to manufacture, and so designed as to be readily assembled or disassembled.

More specifically the object of the invention is to provide an improved cam mechanism for operating the sliding tubular valve, such mechanism including a spring which is located at the side of the cam shaft opposite from the cam-actuated operating lever for the tubular valve, there being link 45 connections between the lever and the spring for uniting said parts.

With these objects in view, and others which will appear as the description proceeds, the invention comprises various novel 50 features of construction and arrangement of parts such as will be set forth with particularity in the following description and claims appended hereto.

In the accompanying drawing, which 55 illustrates one embodiment of the invention, and wherein similar characters of reference

indicate corresponding parts in all the views, Figure 1. is a longitudinal section taken on a plane coincident with the axis of the cylinder; Fig. 2 is a diagrammatic view of the cam for operating the valve; and Fig. 3 is a perspective view of the valve-operating mechanism.

Referring to the drawing, A designates the cylinder of the engine, which cylinder 60 is shown as of the cored-out type to provide a water jacket or cooling chamber 1, and in the cylinder are admission and exhaust passages 2 and 3 arranged at opposite sides or in any other desired order. The cylinder 70 is provided with a fixed tubular bore element 4 which is of uniform diameter and in which reciprocates the tubular valve 5, which is somewhat longer than the bore element 4. Mounted for reciprocation in 75 the valve 5 is the piston 6, which has a wrist pin 7 connected by a rod 8 with the crank 9 arranged within the crank casing or base 10 to which the cylinder A is secured. The head 11 of the cylinder has a reentrant portion 12 which enters the tubular valve 5 and bore element 4 which co-operates with the piston 6 to form an explosion chamber 13. The inlet and exhaust passages 2 and 3 are adapted to communicate respectively 80 through the ports 14, 14^a and 15, 15^a, in the bore element 4 and valve 5 respectively. The inlet port 14^a of the valve is so arranged that it will be out of alignment with the inlet port 14 while the exhaust port 15^a is 85 in registry with the port 15, so that at no time will the explosion chamber 13 communicate with both the inlet and exhaust passages.

The valve operating means comprises a 90 cam 16 mounted on a secondary or half speed shaft 17 suitably driven from the crank shaft 9, and riding on the periphery of this cam 16 is a roller 18 carried on the outer end of a lever 19 that is disposed in the base 10 and fulcrumed at 20, there being a spring 21 to hold the roller 18 against the cam 16. The lever 19 is connected by a link or rod 22 with the lower or outer end of the valve 5. The spring 21 is located directly 100 under the cam shaft 17, and has its lower end detachably engaged with an anchor 23 fastened in the bottom 24 of the base section 25 of the crank case. The upper end of the spring terminates at the plane of division 105 between the lower section 25 and upper section 26 of the crank case and has a hook 27

which detachably engages with a link device consisting of a pair of link members 28 curved to straddle the shaft 17 and spaced apart to accommodate the cam 16. The 5 lower ends of the link members 28 are connected by a pin or bolt 29 over which the hook 27 on the spring engages. The upper ends of the link members 28 are fastened to the extremities of the axle 30 on which 10 the roller 18 rotates. It will be noted that the axis of the spring is coincident with the axis of the cam, and the points of connection of the link element with the lever 19 and spring 21 are disposed directly above 15 and below the center of the cam. This spring exerts a downward pull and maintains the roller permanently in engagement with the top of the cam. By this arrangement it will be seen that the valve-operating 20 means occupies comparatively little space and the parts can be readily detached when the engine is to be taken apart.

The cam 16 serves to move the valve upwardly or inwardly, while the spring 21 moves the valve in the opposite direction. 25 As shown in Fig. 2, the cam is divided into four quarters marked respectively "expansion," "exhaust," "suction," and "compression," to indicate the relation of the valve 30 actuating cam and valve to the piston stroke. The cam is formed of five parts designated *a*, *b*, *c*, *d*, and *e*. During the time the portion *a* of the cam rides under the roller 18 the valve will move downwardly to bring 35 the exhaust port 15^a thereof opposite the port 15, so that on the exhaust stroke of the piston 6 the spent gases will be forced out, the valve remaining open while the portion *b* of the cam rides under the roller 16. This 40 downward movement of the valve is the first step in its down stroke, and by the time the piston reaches the end of its exhaust stroke the valve moves still farther downwardly by reason of the portion *c* of the 45 cam riding under the roller 18; and during this movement the inlet port 14^a of the valve registers with the port 14, this opening of the inlet port occurring during the suction stroke. Before, however, the suction stroke 50 is finished the valve starts upwardly in one continuous stroke by reason of the portion *d* of the cam riding under the roller 18. Both ports are closed during the compression stroke of the piston 8, and the ports remain 55 closed during the entire time the portion *e* of the cam rides under the roller 18. It will thus be seen that a single cam will cause the explosion chamber to be brought into

communication with the inlet and exhaust passages in proper sequence in the cycle of 60 the engine, and there is an absence of wear or loss of compression as is common with the ordinary poppet or mushroom valve.

From the foregoing description taken in connection with the accompanying drawings, the advantages of the construction and method of operation and of the apparatus shown will be readily understood by those skilled in the art to which the invention appertains, and while I have described the 70 principle of operation, together with the apparatus which I now consider to be the best embodiment thereof, I desire to have it understood that the apparatus shown is merely illustrative, and that such changes 75 may be made when desired as are within the scope of the appended claims.

Having thus described my invention, I claim as new and desire to secure by Letters Patent:

1. An engine comprising a cylinder having inlet and exhaust ports, a single tubular valve slidably mounted in the cylinder and having inlet and exhaust ports so related that the inlet ports register when the exhaust ports are out of registry, a piston mounted in the valve, and valve operating means for moving the valve in two steps in one direction to first bring the exhaust ports into registry and then the inlet ports, and 90 for moving the valve in one step in the opposite direction.

2. An internal combustion engine comprising a cylinder having inlet and exhaust ports, a reciprocating tubular valve slidably 95 mounted in the cylinder and having inlet and exhaust ports, a piston mounted in the valve, and valve operating means actuated by the piston, said means comprising a cam having two concentric portions of different 100 radii and eccentric portions so related to the concentric portion that the valve moves in two steps in one direction to first open the exhaust ports and then open the inlet ports while closing the exhaust ports, and 105 for moving the valve in one step in the opposite direction to close both sets of ports, during compression and expansion strokes of the piston.

In testimony whereof I have signed my name to this specification in the presence of two subscribing witnesses.

JAMES KEISTER.
